SAFETY LATCH SHACKLE

Martin Gusbeth, Bronx, N. Y.

Application March 28, 1940, Serial No. 326,411

1 Claim. (Cl. 292—286)

This invention relates to devices for securing doors and like members when in a closed position.

An object of the invention is to provide a hasp or latching means combined with a keeper, and other positive locking means associated therewith whereby security may be obtained.

A further feature is in the provision of an adequate, yet simple, device which assures complete protection against unauthorized opening of a door provided with an embodiment of the invention.

Another purpose is to produce an efficient locking device, which may be used in connection with any preferred type of padlock, and further, having a seal which will unfailingly show evidence of tampering, should such occur.

These and analogous objects are accomplished by the novel and practical construction, combination and arrangement of few and simple parts hereinafter described and illustrated in the annexed drawing constituting a material component of this disclosure, and in which:

Figure 1 is a perspective view of an applied embodiment of the invention, shown in a released or unlocked position.

Figure 2 is a front elevational view of the device, as seen in an engaged position.

Figure 3 is a top plan view of the same, showing the application of a padlock and also a common form of seal.

Referring in greater detail to the drawing, the numeral 10 designates either a conventional door, or one of the swinging elements of a double door, while 11 denotes the other or hinged member.

Fixed on the member 10, as by screws 12, is a keeper base plate 13, in which is rigidly secured a flat, forwardly extending, horizontal keeper 14, containing a narrow slot 15 in its base, adjacent the plate 13 and further provided with a circular opening 16, near its curved outer edge.

The other main member consists of a plate 20 held by screws 21 to the swinging element 11 and fashioned at its outer edge, to present a hinge portion 22 through which passes a pin 23 engaged in loops 24 formed in the outer end of a plate 25.

This plate 25 contains a central elongated slot 26 near its opposite, free end, which is reduced and outturned as at 27; near the extremity is a small perforation 28 in register with the slot 26.

Pivoted on a pin 30 set midway in the length of the plate 25 is a latch 31 having in its underside

a notch 32 defining the inner edge of a detent 33 engageable in the slot 15 of the keeper when the device is in applied position.

An extension 34 of the latch 31 is provided with a perforation 35, registerable with the corresponding perforation 28 in the plate 25. Riveted, as at 36, to the latch 31 is an angle 37 having an upstanding member 38 containing a circular opening 39, registerable with the corresponding opening 16 in the keeper.

A padlock 40, provided with a key 41, has a bail 42 which can be passed through both openings 16 and 39, thereby to prevent raising the latch when the lock is used.

In addition a wire 44 may be passed through the perforations 28 and 35, and the ends of the wire secured by a conventional lead seal 45, thereby clearly indicating if the latch shackle has been molested.

From the foregoing it will be seen that a safe and secure fastening means for doors has been disclosed in their best known embodiments.

However, it will be understood that such changes and modifications may be made as come within the purview of the claims hereto appended.

Having thus described the invention, what is claimed as new and sought to secure by Letters Patent, is:

30 In a self-contained safety door fastening shackle having a plate, one end fixed to the door closely adjacent the free edge thereof and a hinge at the opposite end, and a keeper plate fixed to the jamb of the door in register with the hinge 35. carrying plate, a keeper set in a horizontal plane in said keeper plate, said keeper having a slot adjacent said plate and a circular opening spaced outwardly beyond the slot, a plate attached by said hinge to the first named plate and having 40 an opening adapted to pass over said keeper, a latch plate pivotally mounted on the outer side of said hinged plate intermediate its length, a hook-shaped detent integral with the lower edge of said latch plate adapted to enter the slot in said keeper, a member fixed on said latch plate to extend outwardly therefrom, said member having a circular opening registerable with the opening in said keeper whereby a padlock may secure the latch and keeper against separation 45 and thereby maintain the hinged plate against movement relative to the keeper.

MARTIN GUSBETH.
